UNITED STATES PATENT OFFICE

JEROME WATT, OF CINCINNATI, OHIO

DESIGN FOR A BUILDING

Application filed September 10, 1931. Serial No. 41,055. Term of patent 14 years.

To all whom it may concern:

Be it known that I, JEROME WATT, a citizen of the United States of America, and a resident of Cincinnati, in the county of Hamilton and State of Ohio, have invented a new, original, and ornamental Design for a Building, of which the following is a specification, reference being made to the accompanying drawings, forming a part thereof.

Fig. 1 shows the front elevational view of the building.

Fig. 2 is a plan view of the building shown in Fig. 1.

Fig. 3 is a rear elevation of the building shown in Fig. 1.

I claim:

The ornamental design for a building as shown.

JEROME WATT.
